UNITED STATES PATENT OFFICE.

GUILLAUME MARIE JAFFRENNOU, OF PARIS, FRANCE.

PERCUSSIVE TOOL.

Application filed September 30, 1922. Serial No. 591,461.

To all whom it may concern:

Be it known that I, GUILLAUME MARIE JAFFRENNOU, citizen of the French Republic, residing at Paris, in the Republic of France, have invented new and useful Improvements in Percussive Tools, of which the following is a specification.

This invention has for its object a percussive tool or striking device which may be used in all cases where it is required to execute work by repeated impact such as in the operations of rivetting, chiseling, surface dressing, boiler scale removal, mine and quarry drilling, pavement or road pounding, etc.

The improved tool comprises a casing in which the tool (or tool holder) is guided and wherein a striking member is imparted a circular movement, said member acting in its movement to strike the shank of the tool or tool holder and rebounding freely after each impact in order to clear the tool shank.

Other characteristic features of the invention will appear from the following description.

In the accompanying drawing which shows by way of example two forms of construction of the improved percussive tool, Fig. 1 is a lengthwise section of the apparatus on the line A—A (Fig. 2).

Fig. 2 is a diametral section on the line B—B (Fig. 1).

Fig. 3 is a lengthwise section of a modification along D—D (Fig. 4).

Fig. 4 is a diametral section along C—C (Fig. 3).

As shown in Figs. 1 and 2, the apparatus comprises a casing 1 traversed by a shaft 2 which is driven by a motor either directly or by a flexible transmission with or without the insertion of a clutch 3.

To the driving shaft 2 is keyed a drum 4. This drum drives the striking member which is formed by a ball 6. The combination of the drum 4 and ball 6 is balanced by a heavy part 5. The ball 6 is carried round by the drum 4 by friction and is acted upon by centrifugal force, so that it will always come to the position shown i. e. at the greatest distance possible from the drum axis. It will thus act by repeated impact upon the shank 7 which is held for example in the support 8. The whole machine is moved about by a handle 9.

To afford the release of the striking mass after each impact, the drum 4 has an inner

recess 4^a of suitable shape. Within the drum 4 is also provided a slot 10 of suitable form which gives passage to the shank of the tool.

In the construction shown in Figs. 3 and 4, the drum 4 of the previous construction is replaced by a stud crank shaft 4' to which the driving transmission may be suitably connected. The crank shaft 4' is rotatably mounted in the casing 11 and in the cover plate 12 of the same. Said crank shaft 4' is balanced by two extended portions or cheeks 5 which leave between themselves a channel 13 for the passage of the shank 7 of the tool or tool holder. In the arms 14 of the crank shaft are mounted two rollers 15 which are journaled in their seats and engage at one end into recesses 16 formed in the opposite faces of the striking member 6'. The latter has the form of a cylinder whose generatrix is slightly convex and is a solid part, this being an essential condition in order to withstand the heavy shocks required in certain kinds of work. The rollers 15 are held laterally in their seats by the shoulders 17 on the casing 11 and cover plate 12.

In operation, the crank shaft 4' being rotated, the striking member 6' is entrained by the rollers 14, and this member submitted to centrifugal force takes with respect to the crank shaft 4' and the rollers 15 the position shown in the drawing. In its movement, the striking member comes into contact with the shank of the impact piece 7 and transmits to it a shock on its axis. This shock entirely utilizes the tangential component of the vis viva of the striker. After the shock, the member 6' is again acted upon by the rollers 15 and it is again affected by the centrifugal force, and the shock is thus renewed at each revolution.

The outer diameter of the striker 6', the diameter of the two recesses 16, the diameter of the rollers 15, and the distances *d* and *d'* are so determined that the striker 6' can be released after each shock and can resume its circular movement.

Various constructional modifications in detail may obviously be made in the devices described without for this reason departing from the invention.

Having now described my invention, what I claim as new and desire to secure by Letters Patent is:

A percussive tool comprising in combina-

tion a casing having a passage through which the shank of the tool is adapted to extend; a cover plate adapted to close said casing laterally, a crank shaft across said casing, two cheeks balancing said shaft and leaving between themselves a channel for the path of said shank, two arms integral with said shaft, a striking member having

the form of a cylindrical mass and provided with a circular recess in each of its lateral sides, and two rollers journalled on said arms and engaging into said recesses respectively. 10

In testimony whereof I have signed my name to this specification.

GUILLAUME MARIE JAFFRENNOU.
